PROCESS FOR ROLLING RINGS

Frank B. Bell, Pittsburgh, Pa., assignor to Edgewater Steel Company, Pittsburgh, Pa., a corporation of Pennsylvania

Application April 16, 1932, Serial No. 605,686

2 Claims. (Cl. 29—152.2)

This invention relates to the rolling of metal rings or bands and has for its object broadly the provision of an improved process for producing continuous metal rings or bands having irregular or flanged contours. While the invention will be hereinafter more particularly described as embodied in a process for producing rings or bands adapted to form the cylindrical parts of 5 brake drums which are provided with a multiplicity of radial flanges for heat radiation, it will be readily apparent that the invention has other valuable application.

The invention contemplates the rolling of a band of metal, such as steel, from a bloom by 15 enlarging its diameter and reducing correspondingly its cross-sectional area to provide a smooth cylindrical inner face and a number of outwardly extending or radial circumferential flanges. Considerable difficulty has been experienced in 20 efforts to roll a ring or band of this character and particularly in the flowing of the metal into the flanges upon the periphery as the diameter is enlarged and the sectional area diminished; that is to say, the roll or rolls which define this outer 25 surface are of necessity recessed to receive and define the flanges required, and in the rolling of the ring it has appeared impossible to provide sufficient pressure to force the metal into these recesses as the diameter enlarges.

30 I have discovered that this may be overcome by rolling the flanges upon the bloom before substantial enlargement of its diameter and while the cross-sectional area is relatively large or deep radially of the bloom. Preferably also the formation 35 of these flanges is attended by some reduction in the lateral width of the bloom so that this metal in being displaced tends to force outwardly the outer face of the bloom into the flange producing recesses of the roll determining the circumferential face of the bloom and later the band.

In accordance with my invention the diameter 40 of the bloom is preferably held substantially at constant diameter during the formation of the flanges upon the outer face and the edging or width determining rolls are forced in concur- 45 rently with the pressure of the bloom against the face of the flanged or main roll. After the flanges have been formed upon the face of the bloom 50 little difficulty is encountered in enlarging the diameter, reducing the radial depth of the bloom until final shape is reached, the previously formed flanges being preserved in contour by a sufficient flowing of the metal into them to provide their increased circumferential dimensions.

Numerous other objects and advantages of the invention will be apparent as it is better understood from the following description, which, when considered in connection with the accompanying drawings which illustrate schematically an apparatus adapted to the practice of the process, illustrates a preferred embodiment thereof.

Referring to the drawings:

Figure 1 is a side elevation of an ingot section adapted to be employed to produce a ring or band 10 in accordance with my invention;

Figs. 2, 3, 4 and 5 are sectional views showing steps in the development of the finished ring in 15 accordance with the practice of the process of this application;

Fig. 6 is an enlarged fragmentary section taken through a side of a finished ring or band;

Fig. 7 is a plan view showing schematically an organization of rolls adapted for the practice of 20 the process;

Fig. 8 is a transverse sectional view through the same, certain of the rolls being shown in elevation; and

Fig. 9 is a view similar to Fig. 8 showing the 25 position of the rolls at the end of the rolling operation.

Figs. 5 and 6 illustrate in section a ring or band adapted to form the cylindrical member of an automobile brake drum. The inner surface 11 of this band, generally indicated by reference 30 character 12, is of smooth accurate cylindrical form and is adapted to be engaged by the braking members to accomplish the braking action.

At one side the ring 12 is provided with an 35 outer cylindrical part 13 adapted for attachment by spot welding or otherwise to the side or wedge member of the drum. The ring 12 is provided with a plurality of central circumferential outwardly extending flanges 14 and an edge flange 40 15 which are provided for radiation of the heat in braking.

In accordance with the invention the band 12 is formed from a single ingot section, generally indicated by reference character 16. The ingot section 16 is first flattened and partially perforated at 17 as indicated in Fig. 2. The perforation is completed and the opening through the ring somewhat enlarged as indicated at 18 in Fig. 3. The bloom thus provided is preferably somewhat 50 thicker than the width desired in the finished ring or band 12 and my invention contemplates the rolling of the bloom of Fig. 3 into the finished ring with the radially extending flanges 14 and 55 15 by a sequence of steps which may be accom-

plished by a single set of rolls, such as that schematically shown in Figs. 7 to 9.

Referring to Figs. 7 to 9, reference character 21 indicates a main roll provided with alternately arranged flanges 22 and depressions 23 together having contour mating with the contour of the ring, as indicated in Figs. 5 to 9.

The main roll 21 is or may be fixed in position and is adapted for co-operation with a follower roll 24 which is arranged within the bloom and which is movable toward the axis of the roll 21 to force the metal of the bloom against the pressure roll. Two edging rolls, indicated respectively by reference characters 25 and 26, are provided to determine the width of the ring and to engage and diminish the thickness of the bloom. These rolls are movable toward and from each other and together are movable toward and from the axis of the roll 21. Four guide and confined rolls 27 are provided as may be observed in Fig. 7.

In accordance with the invention, the bloom is positioned over the follower roll 24 and pressure is exerted both by the edging rolls 25 and 26 and by the guide rolls to force the outer face of the bloom against the main roll 21, some pressure, of course, being also applied if desired by the roll 24. The guide rolls 27 and the edging rolls 25 and 26 serve to confine the diameter of the bloom during this initial rolling operation and until the flanges 14 and 15 are formed by the alternately arranged flanges 22 and depressions of the main roll. In this operation the bloom is, as has been stated, held against substantial enlargement of diameter and the rolls 25 and 26 are caused to approach each other to somewhat diminish the thickness of the bloom.

After the rolling has proceeded without substantial enlargement of the diameter of the bloom sufficiently to fill the recesses 23 of the main roll 21, the diameter is enlarged, the edging rolls maintaining or substantially maintaining the width of the ring as the enlargement progresses.

It has been discovered that after the initial formation of the flanges 14 and 15 by the main roll and while the bloom is of small diameter, the enlargement may progress and these flanges be preserved in their contour to desired finished form.

It is thought that the invention and many of its attendant advantages will be understood from the foregoing description and it will be apparent

that various changes may be made in the steps and their order of accomplishment of the process described without departing from the spirit and scope of the invention or sacrificing all of its material advantages, the process hereinbefore described being merely a preferred embodiment thereof.

I claim:

1. The process of fabricating blanks for brake drums and the like having a uniformly dense molecular structure circumferentially, which comprises compressing a circular section of a bar of steel axially to form a disk and simultaneously partially perforating the same, completing the perforation and enlarging the same by spreading the metal radially to form an annulus, and enlarging and shaping the annulus to final form by flowing the metal circumferentially while maintaining the axial dimension thereof substantially constant, thus producing substantially uniform stresses throughout the sectional area of the annulus and compressing the same to obtain a relatively dense molecular arrangement adapted to resist strains exerted on a brake drum fabricated from said annulus.

2. The process of fabricating brake drums and the like having a uniformly dense molecular structure circumferentially, which comprises compressing a circular section of a bar of steel axially to form a disk, partially perforating the same and simultaneously completing the perforation and enlarging the same by spreading the metal radially to form an annulus, rolling the internal and external circumferential surfaces of the annulus to provide a flat inner surface and a flanged outer surface, simultaneously rolling the opposed lateral surfaces of the annulus at a point circumferentially spaced from a point where the circumferential surfaces of the annulus are rolled, and thereafter reducing the thickness of the annulus radially and increasing the diameter thereof while maintaining the width and outer circumferential configuration of said annulus constant thus insuring substantially uniform stresses throughout the sectional area of the annulus, and obtaining a relatively dense molecular arrangement adapted to resist strains exerted on a brake drum fabricated from said annulus.

FRANK B. BELL.
